MOUNTED OIL DIP STICK WIPER
OR SIMILAR ARTICLE

Carroll G. Smith, P.O. Box 188, and Gale Z. Brammer,
P.O. Box C, both of Arco, Idaho 83213

Filed Sept. 27, 1968, Ser. No. 13,743

Term of patent 14 years

Int. Cl. D7—99; D12—99
U.S. Cl. D49—23

FIG. 1

FIG. 2

FIGURE 1 is a front isometric view of a mounted oil dip stick wiper or similar article embodying our new design.

FIGURE 2 is a rear isometric view of our invention taken from the side opposite FIGURE 1 and showing a typical dip stick in phantom view.

The broken lines are shown for illustrative purposes only.

We claim:

The ornamental design for a mounted oil dip stick wiper or similar article, substantially as shown and described.
